UNITED STATES PATENT OFFICE.

JOHN GOODWIN, OF SAVANNAH, GEORGIA, ASSIGNOR OF ONE-HALF TO J. F. ALDERMAN, OF SAME PLACE.

STEAM-BOILER FURNACE.

SPECIFICATION forming part of Letters Patent No. 516,647, dated March 20, 1894.

Application filed August 23, 1893. Serial No. 483,823. (No model.)

To all whom it may concern:

Be it known that I, JOHN GOODWIN, a citizen of the United States, residing at Savannah, in the county of Chatham and State of 5 Georgia, have invented a new and useful Steam-Boiler Furnace, of which the following is a specification.

This invention relates to steam boiler furnaces; and it has for its object to provide certain improvements in furnaces of this character whereby a more thorough and complete combustion of the fuel employed will be secured, while at the same time providing means for the consumption of smoke and other products of combustion which are usually passed out through the smoke stack in an unconsumed condition.

To this end the main and primary object of this invention is to construct a steam boiler furnace with special reference to the fire box and fuel devices thereof, to secure not only a complete burning of the fuel, but to always maintain an intense heat throughout the entire furnace.

With these and other objects in view which will readily appear as the nature of the invention is better understood the same consists in the novel construction, combination and arrangement of parts hereinafter more 30 fully described, illustrated and claimed.

In the drawings:—Figure 1 is a perspective view of a steam boiler furnace constructed in accordance with the present invention. Fig. 2 is a central vertical longitudinal sectional view. Fig. 3 is a detail vertical sectional view on the line $x-x$ of Fig. 2. Fig. 4 is a detail in perspective of the live coal dumping grate.

Referring to the accompanying drawings:— 40 A represents a steam boiler furnace of that class usually employed on the ordinary steam-boats, and the walls of which are constructed in the usual manner, but it will of course be understood that the furnace is equally as well applicable for use in connection with locomotive as well as any type of stationary boilers, and said furnace is constructed directly in front of and joined onto an ordinary horizontal flue boiler B, provided with the lower 45 enlarged fire flues C, running into the rear smoke box D, from which smoke box lead the upper series of smaller return flues E, open-

ing at their front ends into the furnace smoke box F. The furnace smoke box F, is formed in the rear top portion of the inclosed furnace 55 A, and has leading from the top thereof an ordinary smoke stack G, carrying off the heat and other products of combustion. The said smoke box F, is inclosed at its bottom by the inclined baffle plate H.

The inclined baffle plate H, is arranged between the side walls of the furnace A, and declines from the upper outer edge of the furnace to a point directly over the lower fire flues C, and below the line of the return flues 65 E, thereby providing a construction whereby the smoke and other products of combustion from the fuel are directed in close proximity to the live bed of coals located below and directly in front of the fire flues C, as will be 70 more particularly referred to.

Suitably supported in position within the lower portion of the furnace A, are a transverse series of stationary grate bars I. The stationary grate bars I, extend from the front 75 door inclosed grate opening J, to a point beyond the center of the fire box, and terminate at their inner ends short of the front end of the boiler located directly beyond and in a line with the fire box, and said stationary grate 80 formed by the parallel series of grate bars I, is disposed sufficiently above the bottom of the fire box to form the ash pit K, within which is placed the ordinary ash pan, in order to provide for the accumulation and removal 85 of ashes and coals when the fire is dumped, and the necessary draft for the fuel is secured by reason of the circulation of air through the ash pit under the stationary grate.

The green coal for the furnace is fed onto 90 the front end of the stationary grate through the upper feed opening L. The upper feed opening L, is suitably arranged in the extreme upper portion of the baffle board or plate H, and is provided with a door M, which is closed over the opening when not in use, and it is to be observed that the portion of the stationary grate directly under the fuel opening always sustains green coal, which remains on that portion of the grate until sufficiently charred to have become coked and in a proper condition to be fed to the other live coal portion of the grate, whereby a hot fire may be maintained and smoke and other

products of combustion consumed. While the front portion of the stationary grate accommodates the green fuel, the rear half or portion is designed to accommodate fuel which 5 is undergoing combustion and is intended to supply live coals onto the inner live coal dumping grate O.

The live coal dumping grate O, comprises suitably connected transverse grate bars P, 10 and is adapted to work in the space between the inner terminals of the stationary grate bars and the front end of the boiler B, directly below the fire flues C, and said dumping grate is mounted on the transverse rock 15 shaft Q. The transverse rock shaft Q, is journaled at its extremities in the side walls of the furnace and is provided with an operating crank R, at one end, and this portion of said rock shaft is journaled in the door sill S, of 20 the door inclosed side grate opening s, which permits of access to the dumping grate when necessary. The crank portion of the rock shaft is provided with a pin opening T, adapted to receive the locking pin t, passing through 25 the outer portion of the sill S, and engaging said pin opening to hold the grate stationary.

At a point intermediate of the door opening s, and the upper feed opening L, of the furnace, one side wall of the furnace is provided with a fuel manipulating opening U, 30 inclosed by a door u, and adapted to allow a suitable stoking iron to be inserted therein, so as to work the live fuel of that portion of the grate onto the inner dumping grate which 35 always sustains a live bed of coal or coke, and the front wall of the furnace is provided at opposite sides thereof directly above the front grate opening J, with the front door inclosed cleaning openings V. The cleaning openings 40 V, admit of a suitable stoking iron or scraper, whereby the side portions of the fire box and grate may be cleaned, and clinkers broken and shoved onto the dumping grate, so that the same may be readily deposited into the 45 ash pit.

Now with the construction described in mind, it is to be noted that in starting the fire in the furnace the dumping grate is first fired with coke until a live bed of such material is 50 maintained thereon. Green coal is now fed onto the front end of the stationary grate through the upper feed opening L, and is shoved along such stationary grate up to the live bed of coals onto the dumping grate, by 55 means of a suitable stoking iron introduced through the front opening J. Now that portion of the green fuel on the rear portion of the stationary grate immediately adjacent to the dumping grate, is fired up from the live 60 fuel on the dumping grate, and it is to be observed that the smoke and other products of combustion emanating from this fuel are deflected by the inclined baffle plate H, to a point directly over the live bed of coals on 65 the dumping grate whereby the same are completely consumed before entering the fire flues of the boiler. As the fire diminishes on

the dumping grate the same is replenished with live fuel by introducing a suitable tool through the intermediate manipulating opening U, as already referred to, and this rear portion of the stationary grate is supplied with green fuel by introducing the stoking iron through the upper feed opening and shoving the green fuel along, but it is to be 75 understood that the green fuel of the front portion of the stationary grate is not moved into the fired portion until it has become coked from the fire in the rear portion of the grate. By this means a more thorough and 80 perfect combustion of fuel is maintained throughout the herein described fire box than in those of most ordinary furnaces.

Changes in the form, proportion and the minor details of construction may be resorted 85 to without departing from the principle or sacrificing any of the advantages of this invention.

Having thus described the invention, what is claimed, and desired to be secured by Letters Patent, is—

1. In a steam boiler furnace, the furnace fire box having front cleaning openings and a side fuel-manipulating opening located at one side thereof intermediate of its front and rear walls, the boiler opening into the rear end of the fire box, a stationary grate arranged within the fire box below the plane of said cleaning and fuel manipulating openings, a live coal dumping grate mounted between the 95 rear end of said stationary grate and the adjacent end of the boiler, and a door-inclosed side grate opening formed in the fire box directly opposite one end of said dumping grate, substantially as set forth.

2. In a steam boiler furnace, the furnace fire box having suitably arranged door inclosed grate openings, front cleaning openings, an intermediate fuel manipulating opening arranged in one side thereof, and a smoke 110 box, a flue boiler opening into the rear end of the fire box and the smoke box thereof, an inclined baffle plate leading from the front upper edge of the fire box to a point immediately above the main lower flues and provided 115 at its upper exposed end with a feeding opening, a stationary grate mounted within the fire box and terminating short of the boiler opening into the rear thereof, and adapted to sustain green and live fuel, a live coal dumping 120 grate mounted between the rear end of the stationary grate and the boiler, and means for dumping and locking said grate, substantially as set forth.

In testimony that I claim the foregoing as 125 my own I have hereto affixed my signature in the presence of two witnesses.

his
JOHN X GOODWIN.
